F. HENNEBÖHLE

AUTOMATIC SPRINKLER ALARM VALVE

Filed Feb. 2, 1925

INVENTOR
Frank Henneböhle.

BY
Albert B. Deem
ATTORNEY

UNITED STATES PATENT OFFICE.

FRANK HENNEBÖHLE, OF CHICAGO, ILLINOIS.

AUTOMATIC SPRINKLER ALARM VALVE.

Application filed February 2, 1925. Serial No. 6,455.

The invention generally relates to valves and has for its object to provide a valve structure adaptable for use in conjunction with an automatic sprinkler system or the like for the purpose of causing an alarm to be sounded when that system is brought to function for its designed purpose.

In its more detailed nature the invention seeks to provide a valve particularly adaptable to use in connection with any of the well known types of thermo-controlled sprinkler systems; which is of a simple and inexpensive construction and efficiently effective, when spliced in the pressure supply line of such a sprinkler system, in causing an audible signal or alarm to be sounded upon the event of a functioning of so much as a single sprinkler unit of that sprinkler system.

With the above and other objects in view the invention further resides in the novel details of construction, combination and arrangement of parts, all of which will be first fully described in the following specification, particularly pointed out in the appended claim, and illustrated in the accompanying drawing, in which:

Figure 1 is a vertical longitudinal section of a "straight" type of valve embodying my invention and also illustrates, diagrammatically, several adaptations thereof.

Figure 2 is a vertical longitudinal section of an "angled" type of valve embodying my invention.

In the form of the invention shown in Figure 1 of the drawing 1 indicates the body of the valve which, in this adaptation, is of the "globe" type having the usual internally threaded and flanged passage extensions 2 and 3. The extension 2 is adapted to be connected with the pressure supply pipe 4 which is in turn connected with the elevated supply tank (not shown) and is hereinafter termed the inlet, while the extension 3 is connected with the conduit pipe 5 which is adapted to supply the water, under great pressure due to the elevation of the supply tank, to the many sprinkler heads or units (not shown), and is hereinafter termed the outlet.

The body 1 is provided with a cross web 6 bored at 7 to provide a horizontal piston-valve seat.

A piston-valve 8 is vertically slidable in the body and is insertible thereinto through

the extension throat 9 which is screw-cap closed as at 10, the said screw cap being bored at 11 to provide a guide for the vertically extended guide stem 12 of the said valve.

The vertical extension of the valve is provided with a crank receiving pocket, as at 13, and an upper and a lower crank engaging abutment 14.

A shaft or stud 15 is projected into the interior of the body 1 through the wall thereof and has fixed upon the inner end thereof the short crank arm 16 in position for being engaged on top and bottom by the abutments 14 to be moved thereby as the piston valve is moved. The outer end of the stud 15 has fixed thereon a crank arm 17 adapted to be moved when the piston valve is moved for the purpose of causing a warning alarm or signal to be actuated.

In Figure 2 of the drawing is illustrated an "angled" type of valve embodying the invention and in that figure all parts equivalent to like parts in Figure 1 are numbered accordingly with the exponent α added thereto. In this form of the invention it will be observed that the inlet enters the bottom of the valve and that a cross web is unnecessary as the piston valve seat 18 is formed right at the end of that inlet passage.

In Figure 1 I have diagrammatically illustrated several means for connecting the crank arm 17 for audible signal actuation. In full lines I have shown that arm link 19 connected as at 20 with a heavy knocker device 21 pivotally mounted in position for being tripped thereby to fall upon the warning gong or bell 22 when the valve is actuated by pressure loss in the manner soon to be described. In dotted lines I have shown a pull cord connection 23 with a whistle 24 and in dot and dash lines I have illustrated a circuit closer 25 carried by the crank 17 to be moved thereby to close the open energized circuit 26 in which is connected a warning signal bell 27.

In the arrangement shown in Figure 1 the crank 17 will be moved downwardly when the piston-valve is opened. It will, of course, be obvious that by reversing the position of that crank on the stud 15 the same may be made to move upwardly, see Figure 2.

It will be well understood to those familiar

- with the installation and functioning of automatic sprinkler systems that water is supplied to them at a pressure, say for example at about 20 pounds per square inch, so that when some of the sprinkler units are automatically brought into function by heat action they will most effectively function to profusely sprinkle the whole of the area they are designed to cover.
- 10 When my valve is spliced into the pressure supply pipe supplying water to the sprinklers the pressure will be at equilibrium at opposite sides of the piston-valve 8 and the said valve will remain at rest on its seat.
- 15 As soon as pressure beyond the outlet 3 is reduced even in the slightest possible degree, as by the automatic functioning of but a single sprinkler unit, the equilibrium will be upset and the great pressure acting against
- 20 the bottom surface of the piston-valve 8 through the inlet side 2 will unseat the same and forcibly and positively effect movement of the crank 17 to cause an actuation of the warning signal connected therewith.
- 25 To most positively and effectively actuate the warning alarm the crank 17 should have a quick, forcible, and relatively long movement.
- 30 By the peculiar construction and arrangement of piston valve and crank I have achieved the ideal purpose above alluded to.
- 35 The valve 8 is not a common type of valve but is of a combined piston and valve nature having both a seating head and a depending, snugly fitting solid skirt 27 so that the full force of the pressure will positively be directed to the crank action before opening of the valve and free passage of water relieves such crank moving action.
- 40 Without this relatively long piston-like travel, connections made with an ordinary flat valve would only positively act through so small an interval that should any loose play exist between crank and signal connec-

tion, valve action might take place without 45 effecting a signal actuation at all.

A bottom guide cross web 28 may also be provided depending from the solid piston-valve skirt 27.

It should be understood, of course, that 50 the gong, whistle, and electric bell alarm warning devices diagrammatically illustrated in Figure 1 are not shown of proper proportionate size and merely serve to indicate means of adapting the valve to practical use. The warning devices will be made of a size commensurate with the volume of warning they are designed to give.

From the foregoing description taken in connection with the accompanying drawing 60 it is thought the novel details of construction, manner of operation, and advantages of my invention will be readily apparent to those skilled in the art to which it relates.

Having thus described my invention, what 65 I claim is:—

A valve for use in sprinkler systems including sprinkler heads and an alarm adapted to be sounded upon function of one or more sprinkler heads or other leakage; said 70 valve comprising a housing having an inlet, an outlet, a valve seat interposed between the inlet and the outlet and a capped valve insertion extension provided with a stem 75 guide; a piston valve having a relatively long solid skirt snugly slidable in the valve seat and having upper and lower guide stem extensions, the upper of which extensions has an upper and lower abutment; and a crank 80 device pivoted to the housing and having a short arm within said housing lying between the upper and lower abutment to be moved thereby when the piston valve is moved and a long arm outside said housing and movable with said short arm for the purposes specified.

FRANK HENNEBÖHLE.
